George P. Gillette,

INVENTOR

By Victor J. Evans

ATTORNEY

P. Hickey

WITNESS:

UNITED STATES PATENT OFFICE

GEORGE P. GILLETTE, OF LAKE WORTH, FLORIDA

TOY GUN

Application filed February 10, 1930. Serial No. 427,300.

This invention relates to toys of a type and design for the discharging of elastic projectiles.

One of the principal objects of the invention 5 contemplates the provision and arrangement of a trigger and ejector for the projectile.

Another object of the invention consists of a mounting for the trigger whereby the latter 10 may be shifted to occupy its respective positions without binding.

More specifically stated the trigger is normally and yieldingly induced to occupy releasing position.

15 With the above and other objects in view, the invention further consists of the following novel features and details of construction, to be hereinafter more fully described, illustrated in the accompanying drawings and pointed out in the appended claim.

In the drawings:—

Figure 1 is an elevation of the present invention showing by full and dotted lines the 25 relative positions of the trigger.

Figure 2 is a top plan view of the invention.

Figure 3 is an enlarged fragmentary sectional view of the handle of the toy gun and the trigger and particularly illustrative of the exact construction involved.

30 Referring to the drawings in detail wherein like characters of reference denote corresponding parts, the reference character 10 indicates generally the barrel of the present form of toy gun or pistol and 11 the handle therefor depending from the under side thereof. The rearmost surface of the handle 11 is provided with long and short obliquely inclined surfaces 12 and 13 respectively leading, as at 14, to one side of the central point in its length. The taper of the longer obliquely inclined surface 12 being more radical than that of the surface 13 for purposes to be better understood in the following description of the invention.

40 The trigger member, alluded to in the foregoing and as indicated at 15, is of elongated relatively flat formation and provided with an opening 16 therein eccentrically thereof 45 for registration with the meeting point 14

for the inwardly and obliquely inclined surface portions 12 and 13. The mounting for the trigger 15 may be in the nature of a nail or other fastening, such as indicated at 17, extending for an appreciable portion of its 55 length within the handle 11 from the point 14. The shank of the form of fastening is also passed through the opening 16 in the trigger 15 and the head 18 of the fastening is spaced from the adjacent surface of the 60 trigger to permit the latter to occupy the dotted line position shown in Figure 1 of the drawings when the projectile is released. The fastening device 17 as better shown in Figure 3 of the drawings is in the nature of a 65 pointed fastening device, thereby facilitating the driving of the fastening device into the handle at the point of intersection of the obliquely inclined surfaces with one another. After the fastening device has been driven 70 home, or rather to such suitable depth as to leave the head portion 18 in spaced relation with the handle, facilitates the mounting of the trigger 15 upon the protruding portion of the shank for both a vertical rocking movement and a horizontal rotary movement. By 75 mounting the trigger as described facilitates the oscillation of the trigger should the application or disconnection of the self-acting elastic band be desired. The head 18 on the 80 pointed fastening device 17 prevents any accidental displacement of the trigger 15 when moved in the dotted line position better shown in Figure 1 of the drawings or when the trigger 15 is subjected to an oscillating 85 or rocking movement.

A retaining element for the trigger 15, indicated as at 19, having engagement with the shorter end of said trigger in the manner shown and connected at its extreme portion 90 with the outermost extremity of the barrel 10 is preferably in the nature of a rubber band or other elastic material whereby said trigger will be yieldingly induced to occupy the Figure 3 position, a form of fastening 95 20 being passed through the retaining element 19 to prevent displacement thereof upon the trigger 15.

The form of projectile employed may be 100 also in the nature of an elastic band, such as

indicated at 21, having its foremost looped end passed about the outermost end of the barrel 10 in a manner similar to that of the connection of the retaining element 19 therewith and having its rearmost extending portion overlapped in the manner shown in Figure 2 of the drawings and to facilitate disposing of the rearmost looped end of the band or projectile 21 between the inclined surface 13 of the handle 11 and the adjacent surface of the trigger 15.

The projectile or band 21 is stretched sufficiently between the end of the barrel and handle whereby the projectile will fly through the air for an appreciable distance. The manner and method of releasing the band-like projectile simply requires the gradual compressing of the trigger and handle or "trigger squeezing".

The invention is susceptible of various changes in its form, proportions and minor details of construction, and the right is herein reserved to make such changes as properly fall within the scope of the appended claim.

Having described the invention what is claimed is:—

A pistol comprising a barrel and handle therefor, said handle having oppositely inclined portions to provide at their point of intersection a fulcrum point, one of said portions being of a greater length than the other of said portions, a self-acting elastic band stretched over the front end of the barrel and for the full length thereof, a trigger of elongated flat formation for the pistol, a headed pointed fastening device passing through the trigger and driven into the handle at the point of intersection of the oppositely inclined portions, the head of the fastening device being spaced from the handle and preventing any accidental displacement of the trigger from said handle, said trigger being mounted on the extended shank portion of the fastening device for both a vertical rocking movement and a horizontal rotary movement, and an elastic retaining element extending around the full length of the barrel and contacting with the forwardmost end of the barrel and with said trigger.

In testimony whereof I affix my signature.
GEORGE P. GILLETTE.
